INVENTOR

ALFRED A. LINSELL

BY *Ira J. Adams*

ATTORNEY

UNITED STATES PATENT OFFICE

ALFRED AUBYN LINSELL, OF BRENTWOOD, ENGLAND, ASSIGNOR TO RADIO CORPORATION OF AMERICA, A CORPORATION OF DELAWARE

ACOUSTIC INSTRUMENT

Application filed July 13, 1928, Serial No. 292,444, and in Great Britain August 30, 1927.

This invention relates to acoustic instruments, and is particularly applicable to loud speakers, gramophones and the like.

It is well known that in many acoustic instruments, more especially those having diaphragms of large area, such as are employed in so-called hornless loud speakers, interference is apt to occur between the sound waves emitted from the front of the diaphragm and those emitted from the back.

One way of minimizing or avoiding such interference is to provide a baffle plate, independent of the diaphragm, and to mount it in such a position with respect to the said diaphragm that sound waves are substantially prevented from passing from front to rear thereof or vice versa.

According to this invention the diaphragm of an acoustic instrument is itself so formed and arranged as to act as a baffle as well as to emit sound, whereby the provision of a separate baffle plate of large size is rendered unnecessary.

The invention is illustrated in the accompanying drawings in which:

Figure 1 shows a side view of an instrument constructed in accordance with my invention,

Figure 2 shows an end view of the instrument of Fig. 1,

Figures 3 to 11 inclusive show modifications of the instrument of Figure 1.

Referring to the construction shown in side view in Figure 1 and end view in Figure 2, an acoustic instrument in this case a loud speaker comprises a cone shaped diaphragm 1 having a free edge and adapted to be impelled in known manner by means of a coil 2 to which currents of acoustic frequency are fed and which is wound upon a ring 3 and immersed in the annular air gap of a magnet system (not shown). The rim of the diaphragm 1 is secured to the inner curved side of an open-ended cylinder 4, halfway along its length. The cylinder lies with its axis

substantially in the same straight line as the axis of the cone, and is at least as long as one eighth of the longest wave length the instrument is desired to reproduce, so that a compressional wave, starting from the edge 50 of the conical portion of the diaphragm and travelling first in the same direction to one edge of the cylindrical portion, then back to the opposite edge thereof, and then back again to the middle line thereof would have travelled a distance equal to at least a quarter of the length of the longest wave it is desired to reproduce.

In the modification shown in Figure 3, the diameter of the base of the cone is less than 60 that of the cylinder, the said cone being secured to the said cylinder by means of an annulus 5 perpendicular to the curved cylindrical surface. In this case the annulus 65 should not be too wide.

In a variation of this construction, illustrated in Figure 4, the annulus 5 is arranged to slope back at an angle to an intermediate line on the curved surface of the said cylindrical portion 4 as shown, or so as to join the 70 edge of the cone 1 to that edge of the cylindrical portion 4 nearest the apex of the said cone.

In another modification, illustrated in Figure 5, the main sound emitting portion 1 of 75 the diaphragm—i. e. that portion to which the cylindrical portion is attached—is flared at the mouth. In this arrangement, for example, the member 1 is so shaped that the part which lies within the cylindrical portion 80 4 appears in section as two substantially circular arcs 1a, 1b, subtending approximately each 90°, and struck each with a radius equal to half the length of the cylinder, so that the two said arcs are normal to the surface of the 85 said cylinder at the point of juncture.

In a further modification the conical portion 1 of the diaphragm, which may be flared at the mouth if desired, is secured to the cylindrical portion at one or other of the circular 90

- edges thereof, or to an intermediate circular line thereon, instead of the middle circular line. Such modifications are illustrated in Figures 6 and 7, the edge of the member 1 being secured to the forward edge of the member 4 in the construction shown in the figure, and to the rearward edge in the construction shown in the latter figure. 5
- In another construction, shown in Figure 8, 10 two conical diaphragm members 1', 1'', are provided and placed apex to apex so that their axes lie substantially in the same straight line, the height of each cone being not less than one eighth of the length of the longest wave it is desired to reproduce. The cones are placed within an open-ended cylindrical member 4, the circular base of each of the said cones being secured to one of the circular edges of the said cylindrical member. 15 If desired, the apices need not be contiguous, but may be joined by a connecting rod 6 or the like, as shown in Figure 9, in which case the shortest distance between the circular edges of the cones should be not less than a quarter of the length of the longest wave length it is desired to reproduce. 20 Means for impulsing the diaphragm members 1' and 1'' are omitted from Figures 8 and 9 for the sake of clearness. 25
- In all the above described constructions, a stationary baffle of known form may, if desired, be provided. Such a baffle may comprise a board or the like 7 of figure 10 having a central hole to receive the diaphragm. In 30 such a case it will be obvious that both the stationary baffle and the "diaphragm" baffle may both be of similar dimensions than would otherwise be the case to obtain the same result if either were used alone. 35
- If desired a reflector 8, Figure 11 may be provided in rear of the diaphragm. The surface of such a reflector should present substantial circumferential symmetry with respect to the axis. 40
- Having now fully described my invention and the manner in which the same is to be performed, I claim:— 45
1. An acoustic device comprising a diaphragm sufficiently large to set up self-sustaining sound waves in free air, a cylindrical baffle member arranged co-axially with said diaphragm, said baffle member being positioned and arranged so that it surrounds the peripheral edge of said diaphragm and so 50 that the peripheral edge of said diaphragm is immediately adjacent a circle on said cylindrical member intermediate the ends thereof, and a non-planar reflecting surface positioned immediately in back of said diaphragm so 55 as to reflect the sound waves set up by the rear of the diaphragm. 60
  2. An acoustic device comprising a conical diaphragm, a cylindrical baffle member surrounding the edge of said conical diaphragm, 65 and a second baffle member surrounding said
- cylindrical baffle member and arranged substantially perpendicular to the axis of said cylindrical baffle member. 70
3. An acoustic device for radiating sound waves comprising a rigid hollow cylindrical member whose length is one eighth of the wave length of the longest sound wave to be radiated, and a vibratile diaphragm secured around its edge to the inside of said cylindrical member. 75

CERTIFICATE OF CORRECTION.

Patent No. 1,844,014.

February 9, 1932.

ALFRED AUBYN LINSELL.

It is hereby certified that error appears in the printed specification of the above numbered patent requiring correction as follows: Page 2, line 37, for the word "similar" read smaller; and that the said Letters Patent should be read with this correction therein that the same may conform to the record of the case in the Patent Office.

Signed and sealed this 12th day of July, A. D. 1932.

(Seal)

**M. J. Moore,
Acting Commissioner of Patents.**
